APPARATUS FOR TREATING COATED PAPER
AND THE LIKEHenry F. Scott, Framingham, Mass., assignor to
Dennison Manufacturing Company, Framing-
ham, Mass., a corporation of Massachusetts

Application September 11, 1930, Serial No. 481,123

4 Claims. (Cl. 91—18)

In the manufacture of coated paper and the like, such as gummed paper and other sheet material coated with indurated composition, it is usually necessary to produce a network of cracks in the coating after it hardens to reduce its curling tendency. Heretofore, this has usually been accomplished by drawing the paper over a series of knife-edges at a pronounced angle and under heavy tension. This procedure 5 has been unsatisfactory for many reasons chief of which are the following. Inasmuch as the knife-edges incline from end to end in opposite directions at approximately forty-five degrees to the path of the paper, breaker machines for 10 wide bands of paper involve high first cost and require extensive floor space. Inasmuch as the knife-edges require frequent sharpening the maintenance cost is considerable. The paper is subjected to relatively high tension and consider- 15 able power is required to draw the paper over the sharp edges. There is great danger of the paper tearing as it passes over the edges and when it does tear the machine must be shut down for rethreading. At each end of 20 a roll of paper and on each side of a rupture, the machine fails to break the coating throughout a length approximately equal to the length of the machine, thus resulting in large percentages of waste. The knife-edges tend to 25 roughen the uncoated surfaces of the paper against which they rub, necessitating a recalendering operation; they also introduce a reverse curl, commonly called reverse, which ordinarily 30 requires the paper to be drawn over one or more auxiliary edges bearing against the coated side. The only practical way of regulating the non-curling effect of the knife-edges on the paper, especially while the machine is in operation, is to vary the tension on the paper. Practi- 35 cally such machines are applicable only to stock in roll form in contradistinction to stock in sheet form.

Objects of the present invention are to avoid the aforesaid disadvantages and to provide a 45 method and machine which involves much lower first cost, which requires far less floor space, which incurs small maintenance cost, which requires little or no tension on the paper and less power, which is much easier to thread and less likely to tear the paper, which involves substantially no waste at the ends of each piece of paper, which unlike a knife-edge has substantially no tendency to loosen the surface fibers of the paper and therefore does not necessitate recalendering, which has comparatively 50

little reverse curl and that only longitudinally of the paper so that it may if desired be removed by a single cross-bar extending transversely of the machine so as not to add materially to the length of the machine, which may be readily 60 and accurately adjusted to regulate the non-curling effect without stopping the machine, which is adapted for use on either roll or sheet stock, which will break stock having higher moisture content, thus requiring less 65 time and heat in preparing the stock for the breaking operation, which can be incorporated in the coating and/or calendering machine, thereby reducing the number of separate operations, and which is generally superior to prior 70 methods and machines for the purpose.

In one aspect the present invention involves producing in the paper or other sheet material a row of juxtaposed waves of small extent in both length and width and advancing the waves 75 along the paper transversely of the row, thereby to flatten and/or soften the paper. The effect on the paper may be regulated in degree by varying the depth of the waves. A preferred method of producing the waves consists in si- 80 multaneously flexing the paper in two dimensions by producing in the back of the paper a series of juxtaposed indentations of small extent in both of said dimensions and concomitantly producing relative movement of the paper edge- 85 wise thereof, that is moving the paper relatively to the indenting means and/or vice versa, to cause the indentations to trace continuous juxtaposed paths, preferably parallel paths. While the paper is treated as aforesaid it is preferably 90 supported on its coated side by a soft support such as a layer of moderately soft rubber, either in the form of a covering on a drum or a belt sliding over a table, the paper being indented into the soft support by surfaces curved in two 95 dimensions and the aforesaid waves therefore being produced in the soft support as well as in the paper. Said curved surfaces are preferably rolling surfaces so as to avoid abrasion, reduce wear, and minimize the power required. While 100 these rollers may be integrally interconnected in the form of circumferential corrugations on a small drum or shaft, the corrugations being either circular or wavy circumferentially of the axis, they are preferably in the form of separate 105 balls. The convex surfaces are preferably arranged in a row (straight, curved or staggered) in which case the aforesaid relative movement is either perpendicular or oblique or otherwise transverse of the row. By using a plurality of 110

rows and staggering the indenting surfaces of successive rows, all portions of the paper may be thoroughly flexed without making the balls or the like excessively small.

5 For the purpose of illustrations three typical embodiments of the invention are shown in the accompanying drawing in which;

10 Fig. 1 is a side elevation of one embodiment, largely diagrammatic but showing parts in section;

Fig. 2 is a section on line 2—2 of Fig. 1;
Fig. 3 is a bottom plan viewed from the line 3—3 of Fig. 2;

15 Fig. 4 is a side elevation of another embodiment, showing parts in section;

Fig. 5 is an enlarged top plan of parts of Fig. 4; and

Fig. 6 is a side elevation of still another embodiment, showing parts in section.

20 The particular embodiment of the invention illustrated in Figs. 1, 2 and 3 comprises an endless belt 1 movable in the direction of the arrow by revolving drums 2 and 3, a stationary table 4 to support the upper stretch of the belt, a take-up reel 5 to receive the gummed paper 6 or the like after it is broken, idler rolls 7 and 8 for holding the paper 6 in frictional engagement with the belt 1, and disks 9 having down-turned rims 10 for confining groups of balls 11 which 25 may be ordinary steel balls such as commonly used in bearings. The disks 9 are rotated about central axes by means of shafts 12, thereby to cause the balls 11 to roll over the paper as the paper feeds through the machine in the direction 30 of the arrow. If desired, the lower faces of the disks 9 may be unpolished to increase the friction between the disks and the balls thereby to increase the rotational tendency imparted to the balls by the rotating disks. If the axes of 35 the shafts 12 are fixed the disks are provided in sufficient number and in such locations as to roll the paper 6 throughout its entire width. However in some cases it is preferable to move the shafts 12 transversely of the paper, either in 40 a straight line or along arcs of circles, as they are being rotated about their own axes, thereby to roll the entire surface of the paper with a lesser number of disks.

45 While the operation of this particular embodiment of the invention will be evident from the above description of the generic invention, it may be noted that the paper moves at the same linear velocity as the belt 1 and that the balls indent the paper into the soft surface of the belt sufficiently to produce a fine network 50 of cracks throughout the gum or other hardened coating on the paper, the coated surface of the paper preferably being directed toward the belt instead of toward the balls. The pressure on the balls depends upon a number of factors but in breaking ordinary gummed paper with balls one-quarter inch in diameter the rubber belt preferably has sufficient give to require approximately one-half pound pressure per ball. The 55 only substantial tension or pull to which the paper need be subjected is the small amount exerted by the take-up roll 5 which is required to remove the small amount of reverse by drawing the paper over the blade 13.

60 The embodiment illustrated in Figs. 4 and 5 is similar to that shown in Figs. 1 to 3 except that the balls 11 are arranged in rows transversely of the paper, are retained in position by slotted plates 14 and are pressed against the

paper by freely rotatable cylinders 15 resting upon the balls. The pressure of the balls upon the paper may be determined either by predetermined the weight of the cylinders 15 or adjustable springs may be associated with the cylinders 15. As shown in the plan view of Fig. 3 the balls of each two rows are not only staggered with relation to each other but with relation to the balls of the other two rows so that the balls of the four rows trace paths along the paper, the center lines of which are spaced apart only one-fourth the diameter of each ball.

80 The third embodiment chosen for the purpose of illustration comprises a flexible belt 16 trained over guide rolls 17 with sufficient slack to form a depending loop between the two upper rolls, feed and take-up rolls 18 and 19 for feeding the paper or the like through the machine, a plurality of rows of balls 20 resting on the paper in the depending loop, stationary guides 21 surrounding the group of balls for holding them in position and a revolving cylinder 22 for pressing the balls against the paper. While the cylinder 22 may be positively driven at a peripheral velocity equal to the linear velocity of the belt 16, 90 it is preferably driven solely through the medium of the balls which in turn are driven by frictional engagement with the paper.

95 It should be understood that the present disclosure is for the purpose of illustration only 105 and that this invention includes all modifications and equivalents which fall within the scope of the appended claims.

I claim:

1. Apparatus for treating paper and the like 110 comprising a plurality of rows of surfaces convex both longitudinally and transversely of the rows, and means for producing relative movement of the paper and said surfaces edgewise of the paper and transversely of the rows while the 115 paper is indented by said surfaces, the surfaces of successive rows being staggered with respect to the direction of said relative movement.

2. Apparatus for treating paper and the like 120 comprising a plurality of rows of rollers rotatable about axes extending longitudinally of the rows, the periphery of each roller being convex longitudinally of the rows, and means for producing relative movement of the paper and rollers edgewise of the paper transversely of the 125 rows, while the paper is indented by the rollers, the rollers of successive rows being staggered with respect to the direction of relative movement.

3. Apparatus for treating paper and the like 130 comprising a plurality of rows of balls rotatable about axes extending longitudinally of the rows, and means for producing relative movement of the paper and balls edgewise of the paper and transversely of the rows while the paper is indented by the balls, the balls of successive rows 135 being staggered with respect to the direction of relative movement.

4. Apparatus for treating paper and the like 140 comprising a plurality of balls for indenting the paper, the balls being closely arranged in a group extending both transversely and longitudinally of the paper, and means for producing relative movement of the paper and balls parallel to the paper while the paper is indented by the balls, 145 successive balls being staggered with respect to the direction of movement.

HENRY F. SCOTT.
